UNITED STATES PATENT OFFICE.

JONATHAN PETERSON, OF BROOKLYN, NEW YORK, ASSIGNOR TO COMBINATION MACHINE COMPANY, OF NEW YORK, N. Y., A CORPORATION OF DELAWARE.

TOBACCO PACKAGE OR CONTAINER.

Application filed July 17, 1923. Serial No. 652,064.

REISSUED

To all whom it may concern:

Be it known that I, JONATHAN PETERSON, a citizen of the United States, and resident of Brooklyn, in the county of Kings and 5 State of New York, have invented certain new and useful Improvements in Tobacco Packages or Containers, of which the following is a specification.

My invention relates to packages or containers especially well adapted for packing tobacco and particularly sliced plug tobacco in small quantities for pocket use of individual consumers.

Sliced plug smoking tobacco has heretofore been packed in hinged covered sheet metal boxes in order to keep the tobacco fresh and moist and particularly to keep the thin slices from being broken while in the package. Such metal containers are expensive, and add very materially to the cost 20 of the package.

An important object of the present invention is to dispense with such metal containers and to provide a package or container for moderate quantities of sliced plug tobacco suitable for pocket use of individual consumers, consisting largely of paper, and in a particular embodiment, as herein enclosed, consisting entirely of tinfoil and paper, which while not absolutely rigid has sufficient strength and stiffness to preserve its form and effectively protect the slices of tobacco from breaking or crumbling, is very much cheaper than the metal container, is 35 thin, compact and of convenient shape for pocket carrying, preserves the tobacco in fresh condition until the package is opened, and is easily opened and closed after the original opening to permit one slice of tobacco to be withdrawn at a time.

The characteristics and advantages of the invention are further sufficiently explained in connection with the following detail description of the accompanying drawings, 45 which shows one representative embodiment of the invention. After considering this embodiment, persons skilled in the art will understand that many variations may be made within the principles of the invention, and I contemplate the employment of any structures which are properly within the scope of the appended claims.

Figure 1 is a perspective view showing the different container materials or "blanks" 55 in spaced, superposed relation.

Figure 2 shows the inner container or "tray" filled with tobacco, and the inner and outer wrappers associated with the box and partly folded.

Figure 3 shows the wrapper formation 60 completed but not closed.

Figure 4 is a detail showing one of the outer wrapper flap connections.

Figure 5 shows the closure end fold formation of the outer wrapper, the closure 65 members in an intermediate, or partly open position.

Figure 6 shows the top or upper face of the completed package.

Figure 7 shows the bottom thereof. 70

The container as here shown and described, consists, in a preferred form of the invention, of an inner container A which may otherwise be identified as tray or box, an intermediate wrapper B, which might in some 75 cases be a single sheet of material, but preferably is a composite wrapper consisting of a sheet of rather thin paper p and a sheet of tinfoil t, which is usually of quite substantial thickness, the paper and foil being 80 usually secured together by spaced strips of adhesive a, and an outer wrapper or cover C, which is usually paper of substantial thickness and of suitable quality to provide the desired "finish" or decorative appearance 85 of the completed package. The outer face of the cover sheet is usually imprinted with any suitable indicia 1, Figure 6.

The tray A is usually of cardboard of moderate thickness, to provide a certain interior stiffening or reenforcement of the package. It consists of a central or body section 2, side wings 3 and end wings 4, and the blank is suitably creased or scored and the wings are folded up as shown in Figure 95 2. The tobacco contents, consisting in the present example of a plurality of slices of sliced plug tobacco, usually arranged in two rows, is placed in the tray, the tobacco contents coming flush with the edges of the upturned wings 3 and 4.

The filled tray is placed upon a central or body portion 5 of the composite intermediate wrapper B as shown in Figure 2. This composite wrapper is cut to provide 105 side wall portions 6 and end wall portions 7, corresponding substantially to the side and end walls of the tray. Triangular wings 8 are provided extending from the end wall member 7, these wings being de- 110

signed to lie upon the tobacco contents of the package near the ends thereof. A front cover or closure flap 9 extends from one of the side wall portions 6 and a rear cover flap 10, usually wider than flap 9, extends from the other side wall portion.

At the intersections of the triangular flaps 8 and the closure flaps 9 and 10, right-angled fold or corner flaps 11 are provided. 10 Before the intermediate wrapper and the tray are associated with the outer wrapper, or at least before the fold formation of the outer wrapper is produced, the wall and wing portions 7 and 8, and the wall and 15 closure flap portions 6 and 9 and 6 and 10 are folded up at right angles to the bottom section 5 in substantially the position shown in Figure 3, and the corner flaps 11 are then folded as indicated in Figure 3, the 20 folded flaps usually being turned down flat against end walls of the package, as there shown.

The embryo package consisting of the tray and intermediate wrapper is now, or 25 it may have been previously, placed upon the outer wrapper C, occupying the central or body portion 15 thereof. The wrapper also has wall portions 16 corresponding to the side walls of the tray and inner wrapper, 30 end wall portions 17, end flaps 18 extending from the end wall portions, and front and rear closure flaps 19 and 20 extending from the side wall portions 16. The wrapper is preferably formed so that when its parts 35 are completely folded and secured it provides a neck or open mouth of substantial depth, as shown in Figure 3. To secure this mouth or neck formation the blank is provided with sealing flaps 21 which are 40 folded along the dotted lines 22, 23 and 24 in completing the neck or closure formations. The outer wrapper wall portions 17 and end flaps 18, front wall portions 16 and rear closure flaps 19 and 20, are now turned 45 up at right-angles to the body section 15, (Fig. 1) and the parts are secured by folding the sealing flaps 21 along the dotted lines above mentioned, corner folds being produced along the lines 24, Figure 3 and 50 the main portions of the flaps being turned over and secured adhesively to faces of the front and rear flaps 19 and 20 respectively, as also clearly shown in Figure 3. The package is now completed except for closing 55 the mouth or neck, which consists of members 18, 19, and 20 of the outer wrapper, with the cover or closure flaps 9 and 10 of the intermediate composite wrapper standing up against the inner faces of the outer 60 wrapper flaps 19 and 20 respectively, as clearly shown in Figure 3.

To properly close the package, the end flaps 18 are now folded along the diagonal lines 25, and these lines may be produced 65 in the folding of the closure parts, or they

may be provided in the form of creased or scored lines on the blank, as shown in dotted lines, Figure 1. The folding of the end flaps 18 along the dotted lines, as shown in Figure 5, produces substantially triangular end closure flaps or tongues 30 adapted to overlie flaps 8 of the intermediate wrapper, and bellows fold portions 31 which lie between the tongues 30 and front and rear cover flaps 9 and 10 of the intermediate wrapper, and sufficiently retain those flaps against the wrapper flaps 19 and 20; or in other words, the intermediate wrapper flaps are located between the bellows fold members 31 and the wrapper flaps 19 and 20, so that when the package is opened the intermediate wrapper flaps will be raised along with the outer wrapper neck, giving easy and quick access to the package contents.

The neck or closure parts are now folded completely down producing the complete tightly closed, flat and rectangular package, as shown in Figure 6. Closure flap 20 may be sealed adhesively, or this may in some cases be dispensed with and the package may be sealed only by a revenue stamp 40 applied over the flap 20 and with its ends overlying the ends of, and adhesively secured on the bottom of the package, as sufficiently shown in Figure 7.

It is desirable in some cases to provide a conveniently operated device for securing flap 20 temporarily after the package has been first opened, so that it can be easily resecured after each slice of tobacco is removed. For this purpose a rubber band 41 is placed about the package over flap 20 near the free end thereof, in the position shown in Figure 6, and the rubber band may desirably be secured in position by the revenue stamp, as also shown in Figures 6 and 7.

To initially open the package with the rubber band and revenue stamp arranged as described, it is only necessary to tear away the portion of the stamp overlying flap 20, and then the rubber band may be pulled away from the top of the package and will remain attached to the bottom of the package by end portions 49 of the stamp. Cover flap 20 is then raised, whereupon the entire neck structure is lifted to approximately the position shown in Figure 3, to permit the easy withdrawal of a slice of tobacco, and then may be easily reclosed, and in fact the closure members return to closed position automatically when closure flap 20 is depressed. The rubber band is then snapped around in normal position, as shown in Figure 6, and the package is ready to be slipped back into the pocket.

The inner cardboard container or tray, reinforced by the intermediate wrapper and outer wrapper, provides ample stiffness to prevent crumbling or breaking of the to-

bacco contents, although the package is not absolutely rigid. The intermediate wrapper of composite paper and foil, preserves the moisture and freshness of the tobacco.

- 5 The described construction obviates the necessity for using sheet metal boxes for small quantities of tobacco of this character, and an immense saving is therefore effected in the cost of such metal containers, 10 and a given quantity of tobacco can be sold at a lower price, or greater quantity can be sold at the usual price, than has heretofore been possible.

I claim:

- 15 1. As a new article of manufacture, a thin and approximately flat tobacco package for convenient pocket use, which dispenses with a metal container and has sufficient strength and stiffness to protect the tobacco 20 contents, comprising an inner tray of sheet material of substantial stiffness, a quantity of tobacco substantially filling the tray, an intermediate wrapper including tinfoil substantially enclosing the tray and tobacco 25 and having top flaps movably overlying the tobacco contents, and an outer paper wrapper of substantial thickness formed and secured about the tray and inner wrapper and having closure means including an 30 outer flap, said closure means being constructed and arranged to be folded down flat upon the package top with said outer flap uppermost, to completely cover and close the package.

- 35 2. As a new article of manufacture, a thin and approximately flat tobacco package for convenient pocket use, which dispenses with a metal container and has sufficient strength and stiffness to protect the tobacco 40 contents, comprising an inner tray of sheet material of substantial stiffness, a quantity of tobacco substantially filling the tray, an intermediate wrapper including tinfoil substantially enclosing the tray and tobacco 45 and having top flaps movably overlying the tobacco contents, an outer paper wrapper of substantial thickness formed and secured about the tray and inner wrapper and having closure means including an 50 outer flap, said closure means being constructed and arranged to be folded down flat upon the package top with said outer flap uppermost, to completely cover and close the package, and a revenue stamp 55 secured over said outer flap and across the ends and upon the bottom of the package.

- 60 3. As a new article of manufacture, a thin and approximately flat tobacco package for convenient pocket use, which dispenses with a metal container and has sufficient strength and stiffness to protect the tobacco 65 contents, comprising an inner tray of sheet material of substantial stiffness, a quantity of tobacco substantially filling the tray, an intermediate wrapper including tinfoil sub-

stantially enclosing the tray and tobacco and having top flaps movably overlying the tobacco contents, an outer paper wrapper of substantial thickness formed and secured about the tray and inner wrapper and having closure means including an outer flap, said closure means being constructed and arranged to be folded down flat upon the package top with said outer flap uppermost, to completely cover and close the package, and an elastic band normally located about the package and passing over said outer flap and secured to the bottom of the package so that the upper stretch of the band may be readily removed to permit the package to be opened.

4. As a new article of manufacture, a package of sliced plug tobacco dispensing with a metal container and of sufficient strength and stiffness to prevent crumpling or breaking of the plug slices, and thin and approximately flat for convenient pocket use, comprising an inner tray of paper of substantial thickness, a plurality of superposed flat slices of sliced plug tobacco 90 therein, an intermediate composite wrapper of foil and paper substantially enclosing the tray and tobacco, and including top flaps movably overlying the tobacco contents, and an outer paper wrapper of substantial thickness formed and secured about the tray and inner wrapper and having a tubular neck including a closure flap longer than the main mouth contour of the neck, ends of the neck being provided with bellows folds so 100 that the neck may be folded down flat upon the package top with said closure flap uppermost to completely cover and close the package.

5. A tobacco package comprising an inner 105 tray of fibrous sheet material, a plurality of slices of sliced plug tobacco substantially filling the tray, an intermediate composite wrapper of foil and paper formed about the tray and having closure flaps, and an outer wrapper formed about the inner container and conforming to the shape of the tray, and having front and rear closure flaps and end fold formations arranged to normally retain the closure flaps of the intermediate wrapper against the outer wrapper closure flaps.

6. A tobacco package comprising an inner 110 tray of fibrous sheet material, a plurality of slices of sliced plug tobacco substantially filling the tray, an intermediate composite 115 wrapper of foil and paper formed about the tray and having closure flaps, and an outer wrapper formed about the inner container and conforming to the shape of the tray, the outer wrapper being formed with a neck 120 including front and end wall portions and a rear wall portion extending above the edges of the other portions, the end wall portions of the neck being folded on diagonal lines to produce tongues and bellows 125 130

5 folds serving to retain the closure flaps of
the intermediate wrapper substantially
against the front and rear wall portions of
the outer wrapper neck, so that the tobacco
contents is conveniently exposed when the
rear wall portion of the wrapper neck is
raised.

7. A tobacco package comprising an inner
tray of cardboard of substantial thickness,
10 having a bottom portion and upturned side
and end walls, a plurality of slices of sliced
plug tobacco substantially filling the tray,
an intermediate wrapper of composite foil
and paper folded about the tray and having
15 triangular flaps adapted to lie on the to-
bacco contents of the tray, and also having
front and rear closure flaps, and an outer
paper wrapper having a body section under-
lying the tray and inner wrapper, side and
20 end wall portions surrounding side and end
walls of the inner-wrapper tray, and a neck
of substantial depth, consisting of a front
flap, a rear flap having a portion extending
considerably above the normal contour of
25 the neck, and end portions having connect-
ing flaps adhesively secured to the front

30 and rear portions, said end portions of the
neck being adapted to be folded on diagonal
lines to produce tuck-folds which retain the
intermediate wrapper closure flaps in posi-
tion against the front and rear wall portions
of said neck.

8. A container for tobacco or similar com-
modities, comprising a cardboard tray, an
inner composite wrapper of paper and tin-
foil having bottom, side and end wall por-
tions adapted to enclose similar portions of
the tray, and also having end cover flaps and
front and rear cover flaps, and an outer
wrapper enclosing the bottom, sides and end
walls of the inner package consisting of the
tray and inner wrapper, the cover also hav-
ing an upstanding foldable neck, one wall of
which has a relatively long closure flap, end
40 portions of the neck being creased for fold-
ing so as to retain the front and rear cover
flaps of the intermediate wrapper and lift
said flaps when the wrapper neck is opened.

45 Signed at 1107 Broadway, in the county
of New York and State of New York, this
16th day of July, A. D. 1923.

50 JONATHAN PETERSON.
